DEVICE FOR HOLDING EYEBROW OR GRAY
HAIR PENCILS

Paul J. Kordish, Mansfield, Ohio

Application March 21, 1952, Serial No. 277,824

5 Claims. (Cl. 132—11)

1

This invention relates to a device attachable to a conventionally formed hair comb, and adapted by reason of its particular construction for supporting a plurality of eyebrow pencils or pencils used to color gray hair for the purpose of disguising the appearance of the same.

Eyebrow pencils and gray hair pencils are both well known, and are widely used. However, it is difficult to apply said pencils to a particular location in a manner whereby the pencils will be held steady and directed along the desired path.

Accordingly, it is the broad object of the present invention to provide a means adapted to support one or more eyebrow or gray hair pencils, and to permit said pencils to be guided steadily along desired paths.

Another important object is to provide a means of the character referred to which, if desired, can be used for penciling eyebrows, and which is at the same time so formed as to hold a series of gray hair pencils in a particular position relative to the teeth of a conventional hair comb, whereby to permit said gray hair pencils to color or disguise gray hairs when the comb is drawn over the scalp in the usual manner.

Yet another important object is to provide a device of the type stated which can be manufactured at a minimum of cost, and which will be adapted to be applied to any conventional hair comb with maximum ease and speed.

Still another important object is to provide an eyebrow or gray hair pencil holder which can be detached from a comb whenever desired, to allow ordinary use of the comb.

Summarized briefly, the invention includes a clip so formed as to be detachably engaged with the back piece and selected, spaced teeth of a conventionally formed hair comb. Mounted upon the clip is a pencil-gripping means, said means comprising one or more pencil support members each of which is attached at one end to the clip, said members having pencil-engaging clamps spaced laterally of the clip and so formed and arranged relative to the clip as to grip eyebrow or gray hair pencils in positions in which said pencils are arranged obliquely to the teeth of the comb and have their tips extended into spaces between adjacent pairs of said teeth. When the device is used to support a plurality of pencils, said pencils are so arranged, due to the relative arrangement of the pencil-engaging clamps, as to converge in the direction of their tips, thus to cause the tips of the pencils to be disposed in a continuous series in which said tips alternate with the teeth of the comb.

2

Other objects will appear from the following description, the claims appended thereto, and from the annexed drawing, in which like reference characters designate like parts throughout the several views, and wherein:

Figure 1 is a side elevational view of a device formed in accordance with the present invention, as it appears when mounted upon a conventionally formed hair comb;

10 Figure 2 is a top plan view of the device and of the comb on which the device is mounted;

Figure 3 is a transverse sectional view taken on line 3—3 of Figure 1; and

15 Figure 4 is a perspective view of the comb-engaging clip of the device.

In the drawings, the reference numeral 10 has been applied generally to a conventional hair comb having an elongated back piece 12 integrally formed with a longitudinal series of comb teeth 14.

The present invention includes a clip designated generally by the reference numeral 16, said clip being of integral formation and being readily formed from a single blank of flat metal material.

20 Alternatively, the clip, as will appear from the description to be provided hereinafter, can be molded of plastic or the like, and it is to be understood that within the scope of the appended claims, I do not desire to be limited to any particular materials.

In any event, the clip 16 includes a flat, generally rectangular plate 18 adapted to be positioned along one side of the comb, in a manner particularly well illustrated in Figure 1 and in Figure 3. The plate 18, along one longitudinal edge thereof, is formed with a flange 20, that extends fully from end to end of the plate in the preferred embodiment of the invention.

25 The flange 20 is so formed as to engage over the back piece 12 of the comb (Figure 3), and to this end is formed to a hook-like, cross-sectional configuration.

30 At opposite ends of the plate 18, I cut the plate inwardly as at 22, to provide portions that are foldable inwardly toward one another to form end flanges 24. The end flanges 24, like the back piece-engaging flange 20, are of hook-like cross-section, said end flanges being adapted for engagement about selected, spaced teeth 14 of the hair comb.

35 A pencil-gripping means has been designated generally at 26, and includes one or more pencil support members each of which is of integral formation. The pencil support members are of

like construction, and hence, the description of one will suffice for all.

Each pencil support member includes an elongated, straight, intermediate portion 28 that extends laterally from the plate 18 (Figure 3) and is disposed obliquely to the plane of the plate. At their inner ends, the pencil support members are formed with flat end portions 30 integral with the intermediate portions, said flat end portions being positioned against the outer surface 10 of the plate 18 and being connected to said plate by means of rivets 32 extending through openings 34 formed in the plate.

At their outer ends, the respective pencil support members are formed with annular, split clamps 36 adapted to extend about and springably grip eyebrow or gray hair pencils 38. The clamps 36, in this connection, are so formed as to have their axes arranged obliquely to the plate 18, and hence to the plane of the series of comb teeth 14. As a result, the pencils 38 gripped by the clamps 36 will also have their axes disposed obliquely to the plane of the series of comb teeth, for extension of the tips of the pencils into spaces 40 defined between each pair of adjacent teeth of said series.

As will be noted from Figures 1 and 2, the respective clamps 36 are so disposed, relative to one another, as to cause the several pencils 38 to converge in the direction of their tips, this construction being desired for the purpose of causing the tips of the pencils to be spaced sufficiently closely from one another as to be extendable into adjacent spaces 40 of the comb.

It is obvious that if desired, the device can be used for the purpose of supporting only one pencil 38. This might be desirable if, for example, the user is penciling her eyebrows. In any event, and assuming that the eyebrows are being penciled, it is merely necessary that the user draw the comb along the eyebrows, so as to comb the eyebrows while at the same time coloring them.

If the device is being used to support a plurality of gray hair pencils, the pencils are engaged in the clamps 36 in the manner illustrated in Figures 1 and 2, and the comb is then used in the regular manner. As the comb is drawn through the scalp, the teeth of the comb will align the hairs of the scalp, and will guide the gray hairs into the spaces 40. The gray hairs guided into said spaces will, as will be appreciated, be colored by the tips of the pencils 38 disposed in said spaces.

In mounting the device upon a hair comb, it is preferred that the flange 29 first be hooked loosely over the back piece 12, after which the entire device is pivoted laterally in the direction of the comb, so as to cause the flanges 24 to be forced laterally into spaces between selected teeth of the comb. As the end flanges 24 are forced into said spaces, they will spread the teeth and will hook about the teeth when the device is in the final position thereof illustrated in Figure 3. In removing the device, the teeth would be manually spread for disengagement of the end flanges 24.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention

comprehends any minor changes in construction that may be permitted within the scope of the appended claims.

What is claimed is:

1. A holder for an eyebrow and gray hair-concealing pencil, comprising: a clip adapted for connection to a hair comb having a back piece and spaced teeth, said clip including a plate member, and hook means on said plate member engageable about the back piece and spaced teeth of the comb respectively; and at least one pencil holder carried by the plate of the clip and including pencil-gripping means so arranged relative to the plate of the clip as to support a pencil in angular relation with respect to said plate member for extension of the tip of the pencil into the space between a selected pair of adjacent teeth of the comb.

2. A holder for an eyebrow and gray hair-concealing pencil, comprising: a clip adapted for connection to a hair comb having a back piece and spaced teeth, said clip including a plate and flanges of hook-like cross-section extending along one side and the respective end edges of the plate and adapted to engage about the back piece and selected, spaced teeth of the comb respectively; and at least one pencil holder carried by the plate of the clip and including pencil-gripping means so arranged relative to the clip as to support a pencil in angular relation with respect to said plate member for extension of the tip of a pencil gripped thereby into the space between a selected pair of adjacent teeth of the comb.

3. A holder for an eyebrow and gray hair-concealing pencil, comprising: a clip adapted for connection to a hair comb having a back piece and spaced teeth, said clip being formed from a single blank of flat material shaped to include a flat plate adapted for positioning against the side of a comb, and flanges of hook-like cross-section extending along one side edge and the respective end edges of the plate and adapted to engage about the back piece and about selected, spaced teeth of the comb respectively; and at least one pencil holder carried by the plate of the clip and including pencil-gripping means so arranged relative to the clip as to support a pencil in angular relation with respect to said plate for extension of the tip of a pencil gripped thereby into the space between a selected pair of adjacent teeth of the comb.

4. A holder for an eyebrow and gray hair-concealing pencil, comprising: a clip adapted for connection to a hair comb having a back piece and spaced teeth, said clip being formed from a single blank of flat material shaped to include a flat plate adapted for positioning against the side of a comb, and flanges of hook-like cross-section extending along one side edge and the respective end edges of the plate, and adapted to engage about the back piece and about selected, spaced teeth of the comb respectively; and at least one pencil holder carried by the plate of the clip and including pencil-gripping means so arranged relative to the clip as to support a pencil in angular relation with respect to said plate for extension of the tip of a pencil gripped thereby into the space between a selected pair of adjacent teeth of the comb, said holder having a flat portion at one end attached to said plate, an elongated intermediate portion extending laterally from the plate, and a pencil-engaging clamp at its other end disposed for clampably gripping a pencil in a position in which said pencil is arranged obliquely to said teeth.

5. A device for supporting a plurality of eyebrow and gray hair-concealing pencils, comprising: a clip adapted for connection to a hair comb having a back piece and spaced teeth, said clip being formed from a single blank of flat material shaped to include a plate and flanges of hook-like cross-section extending along one side edge and along the respective end edges of the plate, said flanges being adapted to engage about the back piece and selected, spaced teeth of the comb, respectively; and a pencil holder carried by the plate of the clip and including pencil-gripping means so arranged relative to the clip as to support a plurality of pencils in angular relation to one another for extension of the tips of the pencils gripped thereby into adjacent spaces between selected, adjacent pairs of teeth of the comb, said pencil-gripping means comprising a plurality of pencil support members respectively having flat portions at one end connected to said

10
